UNITED STATES PATENT OFFICE.

NAPOLEON B. DOUGLASS, OF OAKLAND, CALIFORNIA.

COMBINED REVERSIBLE WALL FURNITURE AND DOOR.

1,006,068.

Specification of Letters Patent.

Patented Oct. 17, 1911.

Application filed May 4, 1910. Serial No. 559,365.

To all whom it may concern:

Be it known that I, NAPOLEON B. DOUGLASS, a citizen of the United States, residing at Oakland, in the county of Alameda, and State of California, have invented new and useful Improvements in Combined Reversible Wall Furniture and Doors, of which the following is a specification.

My invention relates to living apartments, and pertains especially to a combined, reversible folding-bed and door.

The primary object of the invention is to provide a reversible structure designed to carry on one or both sides an article of furniture capable of being turned into and out of a closet, and which structure can be turned in a minimum space; furthermore, which structure will serve as a door to give ingress and egress to the closet.

Another object is to provide a reversible structure of this sort which is capable of supporting the great weight usually put upon it, without sag or tendency to break down, and furthermore, to reduce cost of manufacture.

The invention consists of the parts and the construction and combination of parts as hereinafter more fully described and claim 1, having reference to the accompanying drawings, in which—

Figure 1 is a perspective view of the reversible structure. Fig. 2 is a detail in plan of the reversible structure in closed position. Fig. 3 is a similar view with the panel reversed, or in open position. Fig. 4 is a detail of an apartment, showing the structure applied as a door to give ingress and egress to the closet or to another room or apartment.

A is a panel swinging on vertical pivots and carrying on one side a bed 2 or other article of furniture or ornament, which latter is swung into or out of the closet 3, according as the panel A is turned on its pivots, in the manner hereinafter described, said panel A normally serving as a closure or door for the closet.

The manner of mounting the panel A so as to turn and reverse it automatically in as limited a space as possible, constitutes the essential feature of the present invention. These means comprise a rigid truss-like frame or bracket made up of upper and lower arms 5—6 and the connecting bar or rod 7. The peculiarity of this frame made up of the parts 5—6—7 is that it is pivoted

to the back of the door, or rather, the back of the door is pivotally hung on the bar 7, with the arms 5—6 between the two ends of the panel, the ends of the arms being pivoted to the door-frame or casing between the vertical center of the closet opening and the side of said opening, so that the panel A, on being reversed, swings around the supporting frame 5—6—7, rather than inside 65 of said frame or bracket.

A panel with its bed 2 and counterweights may weigh several hundred pounds, and all the weight is carried on the arms 5—6. In fact, the principal weight is carried on the lower arm 6. Therefore, it is essential that the arms should be very strong, and at the same time, being pivoted to the back of the panel, rather than to the ends thereof, they must not interfere in any way with the vertical movements of the bed-frame 2. In practice, the lower frame member 6 is of I-beam section, and the rod 7 is about 1½ inches in diameter. If the closet opening is fifty-eight inches across, the swinging panel A is substantially of the same width, while the arms 5—6 supporting the same are, in practice, about thirteen inches long; and the rod 7 to which they are connected is placed centrally of the panel, while the pivots 8 and 9 of arms 5—6 are disposed about sixteen inches from one side of the door-frame, as represented in Fig. 2, and just behind the panel when the latter is in closed position with the bed 2 within the closet.

The pivot-pins 8 and 9, which constitute fixed centers of oscillation for the arms or bracket members 5—6, preferably seat in metal sockets 10. The lower arm 6 is inclined upwardly from the pivot to its point of connection with the rod 7, so as to clear the floor. Likewise the arm 5 is positioned so as just to clear the top of the casing as the panel swings in and out of the closet 100 opening.

The rod 7 is supported in suitable boxes 11—12—13 on the panel, the lower pair of boxes 12—13 being arranged near together and forming a double bearing for the rod 7 on each side of the arm 6. This double bearing provided by the boxes 12—13 is important for the purpose of preventing the rod 7 from bending or warping. The bearing 12 is made especially heavy, because practically the whole weight of the panel and bed, or other article of suspended furniture, comes

on this bearing 12 which rests directly upon the arm 6. If desired, anti friction rollers 14 may be interposed between the bearing-block 12 and the top of the arm 6.

5 In order to effect the automatic reversal of the panel A by a combined opening and closing movement of the panel, I employ a link 15 which has one end pivoted to the closet sill, as shown at 16, about midway of the width of the door opening; the other end of the link being pivoted to the bottom edge of the panel to one side of the central pivot 7, as shown at 17. Manifestly the link 15 can be attached either to the bottom 10 or top of the panel; the pivot 16 forming a center of oscillation for the link.

In operation, the panel would normally stand in the plane of the closet opening, forming a closure for the same like an ordinary door, with the bed inside the closet, Fig. 2. The front or exposed portion of the panel may be provided with a mirror or any other article of furniture or ornament 20 18. When it is desired to use the bed or reverse the panel, the same is turned on its pivot provided by the rod 7, arms 5-6 and pivots 8-9, so as to carry one edge of the panel out into the room, and cause the other edge to retreat within the closet, as represented by the arrow p, Fig. 2. At the same 25 time the link 15 acts simultaneously as a radius-rod to draw in that side of the panel to which pivot 17 is nearest, and then as the rod 15 passes beyond the plane at right angles to the closet opening, to push this same 30 edge of the panel outward again until the panel and bed stand in reverse positions, Fig. 3; the panel being swung through an arc of 180°, and with the bed now exposed 35 to the room. During this reversal of the panel, the latter is swung around the frame 5-6-7 until it stands behind the frame. That is to say, as shown in Fig. 2, the panel A, when the bed is in the closet, is in 40 front of the arms 5-6 and rod 7, and when the panel is reversed, with the bed outside the closet, the arms 5-6 and rod 7 are in front of the panel, as shown in Fig. 3; yet in these reversing movements the link 5 always 45 remains concealed behind the panel. This manner of hanging the door in a frame or bracket composed of the relatively short arms 5-6 and rod 7 enables the panel to be made the full length of the door or closet 55 opening, and these short arms can be, and are, made so strong that they will support the panel and any reasonable weight which may be put upon it, without any need of supporting casters or the like on the panel 60 or links. In fact, these arms 5-6 and their connecting rod 7, or equivalent, act as a crane about which the panel swings. Furthermore, the panel can swing and reverse in a minimum depth of receiving space. 65 Utilization is made of this method of hang-

ing a bed and reversing a panel for providing ingress and egress from a closet or room or other apartment, in the wall of which this device may be hung. Thus, for instance, as shown in Fig. 4, this panel A is hung on 70 the frame represented therein by the reference numeral 6 (but which frame, it is understood, includes the two arms 5-6 and rod 7 previously described) and reversing link 15. This panel swings in the opening 75 3' which connects two rooms, as 19 and 20, room 20 being an ordinary closet, or it may be a hallway or other room communicating with other apartments. Room 20 may have another door entering into it, as shown at 80 21. Thus it will be seen that the closet or room 20 may be entered from the room 19 by swinging the panel A as a door on its pivots provided by the arm 6 and link 15, or room 20 may be entered through the door 85 21. In either event a person is permitted to enter the closet, or have access to the bed or the space in behind the bed when the bed is in the closet.

The advantage of this construction is 90 manifest, especially in apartment houses where economy of space is of prime importance, and especially where the cutting of a doorway into a room may not afford space wherein to hang a wall-bed, and vice 95 versa.

In my present arrangement the wall-bed and door can be combined and made to occupy an opening only a little larger than an ordinary doorway. 100

Having thus described my invention, what I claim and desire to secure by Letters Patent is—

1. The combination with a wall having a closet space, of a frame having a fixed point of oscillation about a vertical pivot which is located a substantial distance from the side wall of said space, a bed-carrying panel adapted to close the entrance to said closet space, said panel having vertical pivots on said frame, and a link pivoted to the panel and having a fixed point of oscillation for automatically reversing the panel by turning the frame. 105

2. The combination with a wall having a closet space, of a door adapted as a closure for said space, said door being vertically pivoted at its center, a carrying frame to which the door is pivoted, said frame having horizontal supporting arms of less length than half the width of the door and pivoted to one side of the plane of the door to a fixed support, and around which frame said door is adapted to swing through an arc of 180° from a position in front of said pivots to a 110 120 position in the rear of said pivots.

3. The combination with a wall having a closet space, of a door adapted as a closure for said space, said door being vertically pivoted at its center, a carrying frame, to 130

- which the door is pivoted, said frame having horizontal supporting arms of less length than half the width of the door and pivoted to one side of the plane of the door to a fixed support, and around which frame said door is adapted to swing, while sustained in front of the closet entrance, through an arc of 180° from a position in front of said pivots to a position in rear of said pivots, and 5 a link pivoted to the door and coacting with said frame and acting to automatically reverse the door by the swinging of the frame.
4. The combination with a wall having a closet space, of a panel adapted as a closure for said space, and a supporting bracket for 10 the panel, said bracket including an arm pivoted to one side of the panel and adjacent to the center thereof, the other end of the arm having a fixed point of oscillation exterior to the edge of the panel, means coacting with said arm to support the entire weight of the panel thereon and maintain the panel vertical in front of the closet space, and means coacting with the panel 15 automatically to reverse the panel by the swinging of the bracket.
5. The combination with a wall having a closet space, of a panel adapted as a closure for said space, and a supporting bracket for 20 the panel, said bracket including an arm pivoted to one side of the panel and adjacent to the center thereof, the other end of the arm having a fixed point of oscillation exterior to the edge of the panel, means coacting with said arm to support the entire weight of the panel thereon and maintain the panel vertical in front of the closet space, and a link pivoted to the panel between its edge and center and having a fixed 25 point of oscillation.
6. The combination with a wall having a closet or like opening, of a bracket hinged at the top and bottom of the opening and between the sides thereof and at a substantial distance from said sides, a panel pivotally supported on said bracket and reversible about the bracket through an arc of 180°, said panel serving as a closure for the closet space, and means to automatically reverse the panel by swinging the bracket.
7. The combination with a wall having a closet or like opening, of a panel, a vertical rod pivoted to the back of the panel, rigid arms on the opposite ends of the rod and between the ends of the panel, the other ends 30 of said arms having a fixed center of oscillation about which the arms may swing to carry the panel around said center, an article of furniture or ornament carried on one side of the panel and means co-acting with the panel to reverse the latter as it swings about the pivot of said arms.
8. The combination with a wall having a closet space, of a panel adapted as a closure for said space, a vertical rod pivoted to the back of the panel, rigid arms on the rod and between the ends of the panel, the other ends of said arms having a fixed center of oscillation about which the arms may swing to carry the panel around said center, an article of furniture or ornament carried on one side of the panel, and a link pivoted to the panel between its edge and center and having a fixed point of oscillation.
9. The combination with a wall having a closet space, of a panel adapted as a closure for said space, a vertical rod pivoted to the back of the panel, rigid arms on the rod and between the ends of the panel, the other ends of said arms having a fixed center of oscillation about which the arms may swing to carry the panel around said center, an article of furniture or ornament carried on one side of the panel, journal-boxes on the panel in which said rod turns, one of said arms arranged between a pair of said journal-boxes and on which the topmost box of said pair bears and supports the weight of the panel, and means coacting with the panel to reverse the latter as it swings about the pivot of said arms.
10. The combination of a frame pivoted to turn about vertical pivots, a panel pivoted to one edge of the frame and adapted to swing from side to side of said frame, an article of furniture or ornament carried on one side of the panel and a link having a fixed pivot of oscillation and pivoted to the panel between the center and side edge of the latter for automatically reversing the panel when the frame is oscillated on its pivots.

In testimony whereof I have hereunto set my hand in the presence of two subscribing witnesses.

NAPOLEON B. DOUGLASS.
